[57] CLAIM

The ornamental design for a trailer, as shown and described.

DESCRIPTION

FIG. 1 is a perspective view of a trailer showing our new design with one of the side doors in open condition, it being understood that the broken lines are for illustrative purposes only.

FIG. 2 is a side elevational view thereof to a reduced scale, the opposite side being a mirror image of the side shown herein;

FIG. 3 is a rear elevational view thereof to a reduced scale;

FIG. 4 is a top plan view thereof to a reduced scale; and,

FIG. 5 is a front elevational view thereof to a reduced scale.
